PORTABLE ROOM AIR BLOWER

Moritz L. Mueller, Gaithersburg, Md.

Application June 24, 1955, Serial No. 36,674

Term of patent 14 years

(Cl. D62—4)

FIG. 2

FIG. 3

Fig. 1 is a front elevational view of a portable room air blower showing my new design;

Fig. 2 is an end elevational view thereof; and

Fig. 3 is a top plan view thereof.

Both ends of the design, one of which is shown in Fig. 2, are identical.

I claim:

The ornamental design for a portable room air blower, as shown and described.
